DECOKING LANCE

Charles E. Rhein and James J. Bruton, Los Angeles, Calif., assignors to The Linde Air Products Company, a corporation of Ohio

Application August 31, 1932, Serial No. 631,167

15 Claims. (Cl. 158—27.4)

This invention relates to an apparatus for burning carbon and other combustible deposits from tubes and is especially adapted for use in removing the deposit of carbon from the tubes of oil cracking stills.

An object of this invention is to provide an apparatus for this use which shall embody means for heating the cokes to kindling temperature. Another object of this invention is to provide an apparatus of this type wherein provision is made for mixing air with the oxygen which serves to support the combustion or for otherwise diluting the oxygen so that the chemical activity thereof and, consequently, the probability of undesirable cutting or burning action on steel tube walls, is reduced. Yet another object is to provide means for cooling the apparatus and for indicating when high temperatures are approached in the tube. Further objects of our invention are to provide a simple, rugged and inexpensive apparatus for removing combustible deposits from the interior of tubes. These and other objects of our invention will be evident from the following description having reference to the accompanying drawings in which

Fig. 1 is a cross section of an apparatus illustrating one embodiment of the invention, the section being taken on line 1—1 of Fig. 3.

Fig. 2 is a diagrammatic illustration of the apparatus taken in section on the line 2—2 of Fig. 3 and including the handle as well as the head.

Fig. 3 is a section on the line 3—3 of Fig. 1.

Fig. 4 is a section on the line 4—4 of Fig. 1.

Fig. 5 is a section on the line 5—5 of Fig. 1.

Fig. 6 is an end view of the apparatus and Fig. 7 is a section of the handle taken on the line 7—7 of Fig. 2.

In the drawings there is illustrated an apparatus embodying one form of our invention. This apparatus is for convenience hereinafter called a lance; the lance consists of a head portion and a handle portion. The head portion has a tube 10 which is conveniently made of copper and has an outside diameter about $\frac{1}{4}$ inch less than the inside diameter of the tube to be cleaned. This outer tube or casing serves to center the lance in the tube which is being cleaned. However, we have found that it is not necessary that the diameter approach that of the tube to be cleaned as closely as this and if the tube is of variable inside diameter a lance adapted to pass the smaller part will operate satisfactorily throughout an enlarged portion. The tube is provided with a base 11 which is held in the tube by any conven-

ient means such as the set screw 12. The base is provided with a number of grooves for receiving fuel tubes 12 and the water tubes 13 and 14. It is also provided with bores 15 and 16, the former forming an air passage and the latter an oxygen passage. The oxygen passage 16 terminates at an annular groove 17 forming an oxygen distributing space. An oxygen tip holder 21 is secured in the base adjacent the oxygen distributing space. A plurality of oxygen tips are mounted in this holder and in the illustration six of such tips 22 are shown. The lower portion of these tips include an injector portion 24. The ends of the tips are bent, as most clearly shown in Fig. 6, to impart a whirling motion to the oxygen.

An air tube 31 is secured to the central portion of the oxygen tip holder and is in communication with the air passage 15. This tube is provided with a plurality of holes 32 and slits 33 for permitting air to escape to the interior of the lance. Part of this air is drawn in to the oxygen tips through holes 25 in the injectors 24. The purpose of mixing air with oxygen is to dilute the oxygen so that the danger of burning or cutting of the tube walls is minimized. While we could use other materials than air to dilute the oxygen, air serves the purpose very well and is the preferred diluent. It would be possible to dilute the oxygen at places other than the injectors, for example by a single injector in the oxygen supply line. We prefer to dilute the oxygen to concentrations below 90% and have found a concentration of 87% very suitable.

In order to heat the deposit to kindling temperatures we provide a plurality of fuel tips 41. In the drawings we have shown three of such tips. We may burn any type of gaseous fuel in these tips, such as acetylene or ordinary illuminating gas, but we have found butane and/or propane particularly well adapted for such use. The fuel gas is supplied through a pipe 42 forming a part of the handle and is led to a header 43. From the header 43 fuel supply lines 12 lead to the fuel tips 41.

In order to prevent the lance from becoming overheated we provide a water jacket formed by welding or otherwise securing a member 61 to the interior of the tube near the extreme end. The water is supplied through the inlet 13 which extends to the outer end of the water jacket and is removed through the outlet 14. The inlet and the outlet continue along the handle, the inlet being connected to a suitable source of supply and the outlet discharging where the discharge will be under observation. Thus during

the operation of the device the discharge can be watched and if it tends to steam or boil the operator will be aware the temperatures within the tube are becoming so high that care must be used in order to prevent damage to the tube walls.

The handle should be long enough to extend the length of the tube to be cleaned leaving a sufficient length outside the tube for convenience in operation. The handle is formed by a tube 71 supplying air, a tube 72 supplying oxygen, a tube 73 supplying fuel, and tubes 74 and 75 serving as the water outlet and inlet. These tubes are held together in any suitable manner, 15 as by a clamp 76.

The method of cleaning cracking stills with the improved device disclosed in this application is as follows: the still is prepared for cleaning in the usual manner. While various methods of preparing a still for cleaning are practiced the following is believed to be representative. The flow of oil (topped crude or other cracking stock) through the still is stopped and a charge of gas oil is pumped through the still for a period of 20 three hours. The cracking temperature (say 810° F.) and pressure (say 1400 lbs.) at the inlet being maintained. The flow of gas oil is then stopped, the furnace fire shut off and superheated steam at 450° F. is admitted to the system, pushing 25 all the oil out. This steaming is continued for several hours to make certain all vapors and liquids have been thoroughly removed so that it will be safe to remove the junction boxes or return bend plugs; this operation being known 30 as unheading. As soon as the still has cooled down the junction boxes are unheaded. Where exceptionally heavy coke deposits are apt to be encountered, additional steaming of the heaviest coked tubes may be advisable. A junction box 35 torch is then brought up and the junction boxes on several rows of tubes are cleaned so that the decoking operations can start. A suitable junction box torch is illustrated in the patent to W. T. Davis, No. 1,901,803, dated March 14, 1933, or the 40 lance described herein may be used to decoke the junction boxes sufficiently to afford easy entrance to the tube proper. In the case of removable return bends, these are lowered to the ground for decoking. As soon as the junction boxes are 45 cleaned the decoking lance is brought into use. The fuel is turned on and is lighted at the fuel tips. The lance is inserted into the tube and oxygen and air turned on. The carbon is kindled by the fuel and burns in the presence of oxygen. 50 If the proportion of tarry matter in the coke is low the coke spawls and is blown out of the tube by air from tube 31. In this way there is no danger that the carbon will burn in contact with the tube thereby damaging the tube walls. To further minimize danger that the oxygen will cut 55 or burn the tube walls provision is made for diluting the oxygen. The preferred method of diluting the oxygen is by adding air to the oxygen through the injectors 24, although it is evident that we could use other gases to dilute the oxygen and could dilute the oxygen at other places than shown. The fuel serves to bring the coke to kindling temperature and also to reignite the coke should this become necessary. Moreover in 60 case a patch of coke is left adhering to the tube it can be burned off in a subsequent pass through the tube. We have found that the heat from the fuel tips does not add appreciably to the relatively intense heat generated by the burning car- 65

bon deposit in the tubes but that the use of the apparatus is greatly facilitated by the use of such fuel tips which serve to provide pilot flames. During the operation of the lance water is circulated to the jacket at the end of the lance and this 10 serves to cool the lance. It also serves as an indication of the temperatures maintained within the tube since the operator can observe whether or not the discharge from the outlet is boiling. Thus the operator has two means of telling whether the lance is operating properly. In case of failure to spawl there will be an internal evolution of heat close to the end of the lance which will cause the water to approach the boiling point and also the lance will be unable to 15 pass the carbon which does not spawl from the tube walls and failure of the lance to advance at a uniform rate indicates unsatisfactory operating conditions.

It is desirable to place screens and/or a water 20 spray at the exit end of the tube being decoked, so as to prevent flying particles of flaming coke from causing damage.

While we have disclosed one specific embodiment of our invention we do not limit ourselves 25 to the particular type of apparatus shown; numerous modifications within the ambit of our invention will be obvious to those skilled in the art.

We claim:

1. Apparatus for burning deposits from the interior of tubes comprising a cylindrical member 30 adapted to engage the interior of said tubes, a plurality of nozzles fixed with respect to said cylindrical member for forming jets of oxygen, said nozzles being arranged with their ends diverging outwardly and lying in planes at an oblique angle to radial planes passing through the axis of said cylindrical member, and means within said cylindrical member for supplying oxygen to said 40 nozzles.

2. Apparatus for burning the deposit from the interior of tubes comprising a plurality of oxygen tips so arranged to form jets of oxygen arranged to impinge upon the deposit, a conduit for supplying a jet of air longitudinally of the tube, a casing surrounding said tips and said conduit, and means within said casing for introducing air from said conduit to said oxygen tips for diluting the oxygen.

3. A device as claimed in claim 2 in which the casing is provided with water cooling means.

4. A device as claimed in claim 1 in which the means for supplying oxygen includes means for diluting the oxygen.

5. Apparatus for removing the deposit from the interior of tubes comprising a plurality of means provided with orifices for forming jets of oxygen, said means being so arranged as to cause the jets to impinge upon the deposit with a swirling motion, at least one burner for supplying fuel for heating the deposit, a conduit for supplying a blast of air longitudinally of the tube and means for supporting the oxygen jet forming means, the burner and the air blast conduit in relatively fixed 60 position.

6. Apparatus for removing carbon from tubes comprising a plurality of diverging oxygen tips, at least one burner, a casing provided with a cooling chamber surrounding said tips and burner 70 and adapted to engage the tube and means for supplying cooling fluid to said casing.

7. In an apparatus for removing deposits from the interior of tubes, the combination with a plurality of diverging oxygen tips, at least one burn- 75

er, a casing surrounding said tips and adapted to engage the tube, means for supplying fuel to the burner and means for supplying oxygen to the tips, said last mentioned means including means 5 for diluting the oxygen.

8. Apparatus for removing a combustible deposit from the interior of tubes comprising a base, a plurality of diverging oxygen tips mounted on said base, means for supplying an air blast mounted 10 on said base centrally of said plurality of oxygen tips, a jacket surrounding said tips and secured to said base means for supplying a cooling fluid to said jacket, and means for supplying air from said air blast supplying means to said oxygen 15 tips for diluting the oxygen.

9. Apparatus for removing combustible deposits from the interior of tubes comprising a base, a plurality of oxygen tips mounted on said base, said base being provided with conduits for 20 supplying oxygen to said tips, means for supplying an air blast mounted centrally of said plurality of oxygen tips and extending forwardly of the ends thereof, a jacket secured to said base and extending forwardly at least to the ends of said 25 tips and means for supplying a cooling fluid to said jacket.

10. Apparatus for removing combustible deposits from the interior of tubes comprising a base, a jacket surrounding said base and extending 30 forwardly thereof, a plurality of oxygen tips arranged substantially in a circle within said jacket, means connected to said base for supplying oxygen to said tips, and means for supplying air to the interior of said jacket; said means for 35 supplying oxygen to said tips including an injector means between the tips and the base for diluting the oxygen.

11. Apparatus for removing combustible deposits from the interior of tubes comprising means 0 provided with orifices for forming a plurality of oxygen jets, said means being so arranged that the jets impinge upon the deposit to be removed, at least one burner means adapted to heat said deposit, means for forming a blast of air longitudinally of the tube, a handle and means uniting said handle with said jet forming means, said burner and said air blast means.

12. Apparatus for removing combustible deposits from the interior of tubes comprising means provided with orifices for forming a plurality of jets of oxygen so arranged that the jets impinge upon the deposit to be removed with a swirling motion, means for directing a blast of air longitudinally of the tube, at least one burner means for heating the deposit and means including a water cooling jacket surrounding said jet forming means.

13. In an apparatus for removing combustible deposits from tubes, the combination of a base, oxygen distributing means on said base, a plurality of oxygen tips, injector means connecting said tips with said oxygen distributing means, a jacket 15 surrounding said tips and injector means, and a conduit for supplying a diluting fluid to the interior of said jacket adjacent said injector means.

14. Apparatus for removing combustible deposits from the interior of tubes comprising a central tube having apertures in the sides thereof, a plurality of oxygen jet forming means arranged about said central tube, said jet forming means being provided with injectors adjacent the apertures in said central tubes, a casing surrounding 20 said jet forming means, means for supplying air to said central tube and means for supplying oxygen to the injector means.

15. Apparatus for removing combustible deposits from the interior of tubes comprising a base, a central tube mounted on said base, said tube being provided with apertures in the walls thereof near said base, a plurality of oxygen jet forming means arranged about said central tubes, said jet forming means comprising tips extending 30 outwardly and injector means mounted on said base opposite the apertures in the central tube, said base including means for supplying oxygen to said injectors and air to said central tube, a casing engaging said base and surrounding said 35 injectors and the portion of the central tube provided with apertures, and at least one burner having its end adjacent the ends of the oxygen tips and means for supplying fuel to said burner.

CHARLES E. RHEIN,
JAMES J. BRUTON.
